(57) **CLAIM**

We claim the ornamental design for a dry powder inhaler, as
shown and described.

DESCRIPTION

FIG. 1 is a front view of a dry powder inhaler with
mouthpiece retracted;

FIG. 2 is a right side view thereof;

FIG. 3 is a left side view thereof;

FIG. 4 is a back view thereof;

FIG. 5 is a top view thereof;

FIG. 6 is a bottom view thereof;

FIG. 7 is a top-front perspective view thereof;

FIG. 8 is a top-back perspective view thereof;

FIG. 9 is a bottom-front perspective view thereof;

FIG. 10 is a bottom-back perspective view thereof;

FIG. 11 is a front view thereof with mouthpiece extended;

FIG. 12 is a right side view thereof;

FIG. 13 is a left side view thereof;

FIG. 14 is a back view thereof;

FIG. 15 is a top view thereof;

FIG. 16 is a bottom view thereof;

FIG. 17 is a top-front perspective view thereof;

FIG. 18 is a top-back perspective view thereof;

FIG. 19 is a bottom-front perspective view thereof; and,

FIG. 20 is a bottom-back perspective view thereof.

The broken lines on the top and bottom of the dry powder
inhaler illustrate seams that form no part of the claimed
design. All other broken lines illustrate portions of the dry
powder inhaler that form no part of the claimed design.

1 Claim, 18 Drawing Sheets
